United States Patent

Des. 239,710

Patented Apr. 27, 1976

239,710

LIGHT TWIN HELICOPTER

James R. Garrison, Arlington, Tex., assignor to
Textron, Inc., Providence, R.I.

Filed Mar. 31, 1975, Ser. No. 563,506

Term of patent 14 years

Int. Cl. D12—07

U.S. Cl. D12—73

FIG. 1 is a side view of a light twin helicopter showing my new design;

FIG. 2 is a front view thereof; and
FIG. 3 is a top view thereof.

I claim:

The ornamental design for a light twin helicopter, as shown.
